Patented Dec. 12, 1916.

UNITED STATES PATENT OFFICE.

EUGENE A. KUEN, OF CINCINNATI, OHIO, ASSIGNOR, BY MESNE ASSIGNMENTS, TO THE CORCORAN-VICTOR COMPANY, OF CINCINNATI, OHIO, A CORPORATION OF OHIO.

ELECTRIC LAMP.

1,207,771.

Specification of Letters Patent. Patented Dec. 12, 1916.

Application filed August 2, 1915. Serial No. 43,184.

To all whom it may concern:

Be it known that I, EUGENE A. KUEN, a citizen of the United States, residing at Cincinnati, in the county of Hamilton and State of Ohio, have invented certain new and useful Improvements in Electric Lamps, of which the following is a specification.

My invention relates to electric lamps applicable for instance as headlights for automobiles or other vehicles, and has for its object the provision of novel means which are readily assembled for adjusting the incandescent electric light-bulb to proper focus in the reflector and for maintaining the electric light-bulb in adjusted position; further to provide novel means whereby the socket arranged to receive the plug of the electric light-bulb is arranged to be adjusted in the line of the principal axis of the reflector so as to adjust the electric light-bulb to the desired focus in the reflector, either axially or rotatively, or in directions which are the sum of said axial and rotative movements, and for limiting said movements; further to provide novel means for limiting rotative movement of the socket-member, for instance for avoiding tangling or excessive bending of the flexible electric conductor or conductors for the socket; further to provide novel means for limiting axial movement of the socket, whereby a plug may be readily connected with the socket by means of a bayonet connection; further to provide novel means whereby the axial movement of the socket in either direction is limited for permitting the ready attachment of a plug at either end of said socket.

The invention will be further readily understood from the following description and claims, and from the drawings in which latter:

Figure 1 is an axial section of an electric lamp embodying my invention, the socket being shown in side elevation. Fig. 2 is a side elevation of my improved device, the lamp-members and the electric light-bulb being shown partly broken away. Fig. 3 is an axial section of my improved device, taken on the line 3-3 of Fig. 2. Fig. 4 is a cross-section of my improved device, taken on the line 4-4 of Fig. 2, showing the socket in a position of rotative adjustment intermediate of its limits of rotative adjustment. Fig. 5 is a similar view showing the

socket at one of its limits of rotative adjustment. Fig. 6 is a similar view showing the socket at the other of its limits of rotative adjustment. Fig. 7 is a perspective view showing the main parts of my improved device in separated relation. Fig. 8 is an axial section of my improved device, illustrating its application to a double-ended socket; and Fig. 9 is an axial section of the same on the line 9-9 of Fig. 8.

My invention is an improvement upon the electric lamps shown, described and claimed in Letters Patent No. 1,140,893 and No. 1,140,894, granted Charles Harry Fischer, May 25, 1915.

In the present exemplification of my invention, the outer casing is shown at 11 and the reflector at 12, the reflector being shown as of general parabolic form. It is shown received in and secured to the outer casing in suitable manner, as by screws 13, for forming the body of the lamp as a double walled body, the outer wall of which is formed by the outer casing and the inner wall by the reflector, there being a space 14 between said walls, in which, in the present exemplification, the means for permitting adjustment of the socket and for maintaining the socket in adjusted positions are contained.

The front closure of the lamp is shown at 15, and is exemplified as a door provided with a glass 16. The door is suitably mounted on the body, as by means of hinges 17, or the casing, reflector and door may be suitably connected together in other manner, so that if it is desired to have ready access to the electric light-bulb, shown at 18, the front closure may be readily removed in order that adjustment of the light-bulb to the desired focus may be obtained by the manual handling of the light-bulb. If desired, however, the adjustment to the desired focus may be obtained from the outside of the lamp-body, as hereinafter described and as illustrated in Figs. 8 and 9.

A socket-member is provided, to which the electric light-bulb is arranged to be secured, this socket-member being instanced as a socket-tube 21 received in a central aperture 22 of the reflector. A flange 23 acts to support the socket-member in the line of the principal axis of the reflector. This flange exemplifies a lamp-member extending into

the space from one of the body-members and is shown on a flange-piece 24 suitably rigidly secured to the reflector, as by soldering.

The socket-member is provided with plug 5 attaching means, exemplified as bayonet slots 25 in the wall of the socket-member, arranged for receiving the pins 26 of the plug 27, exemplified as the plug of the electric light-bulb. The outer periphery of the 10 socket-member and the inner periphery of the lamp-member therefor are preferably annular and preferably arranged so that the socket-member may have rotary or axial movement, or a movement which is the sum 15 of these two movements, in said flange or lamp-member, a resilient part being provided with relation to which said socket-member has movement, the latter member and said socket-member having complementary coacting surfaces arranged for permitting said movements of said socket-member and holding said socket-member in adjusted positions.

There is a connection between the lamp-member and the socket-member whereby either axial movement or rotary movement or both said movements of the socket-member are limited, and means are further provided comprising a relatively movable member, which, during a portion of the range of rotative movement of the socket-member, is inactive, and during another portion of the movement of the socket-member is active. Thus the socket-member is provided with protuberances 31 and depressions 32 extending in a plurality of directions crossing each other. The coacting member of said surfaces is shown as a shoe 33, which is received through an opening 34 in the flange 23, the 25 inner end of the shoe having a surface which is complementary to the retarding outer surface of the socket-member, as, by forming its inner end tapering for being received in the depressions of the socket-member.

40 The socket-member is provided with a recess 36, the recess being shown as extending lengthwise of the socket-member and provided with the side walls 37, 38, and end walls 39, 40. A finger 41 is received in this 45 recess and is shown on a plate 42, illustrated as a curved plate received about the periphery of the flange, the finger projecting through an opening 43 in the flange and thence into the recess 36. The opening is provided with side walls 44, 45, and with end walls 46, 47, these walls limiting the range of movement of the finger 41.

The shoe 33 is mounted on a spring 51, shown as a band spring, curved to be received about the flange, the band preferably extending more than half way around the flange, so that it will be retained on said flange by its spring pressure, and arranged to be releasably received thereabout. It 65 preferably also is received about the plate

42 for holding said plate in place and preferably providing pressure upon said plate for frictional resistance to movement of the latter.

The end of the spring is curved outwardly, 70 as shown at 52. The construction is such that the spring may be readily pushed about the flange 23 and plate 42 in assembling the parts. The spring urges the shoe 33 toward the socket-member for continuously maintaining resilient contact between said shoe and said socket-member. Proximate protuberances and depressions are closely adjacent to each other for providing minuteness of focal adjustment.

80 The socket is, in the present exemplification of my invention, shown as a two-terminal socket comprising terminals 53, 54, urged toward the terminals 55, 56, of the plug, instanced as the plug of the light-bulb, by 85 means of springs 57, 58, located in the sleeves 59, 60, shown in Figs. 1, 2, 3 and 7 as forming binding posts, from which flexible electric conductors 61, 62, extend to a usual outer socket 63 suitably secured in the outer casing of the electric lamp. The outer electric conducting plug 64 having the flexible electric outer conductors 65, 66, electrically connected therewith, is arranged to be releasably secured in the outer socket 63 by means 90 of bayonet connections 67, for forming electric connection between the conductors 65, 66, and the respective conductors 61, 62, through usual terminals of the outer plug.

95 The sleeves 59, 60, are suitably insulated from the socket-tube 21 by means of a body 68 of insulating material surrounding said sleeves.

100 The plug of the electric light-bulb is arranged to be received in its socket, so that in forming the bayonet connection therewith, its terminals 55, 56, will press the terminals 53, 54, of the socket axially, for making good electric connection therewith, the 105 springs 57, 58, resisting this axial movement.

110 The holding properties of the shoe 33 and spring 51 will ordinarily not be sufficient to counteract the manual force exerted in rotary and axial lines in connecting the plug with the socket-member, in consequence of which the socket-member will be pushed axially and rotated by the plug. This axial movement is a rearward movement when the plug to be attached is the plug of the electric 115 light-bulb.

120 It is sometimes desired that the adjustment of the electric light-bulb to desired focus in the reflector be accomplished from the outside of the lamp and that the outside plug for connecting the outside electric conductors be attached to the socket-member. I have exemplified such a structure in Figs. 8 and 9, in which the parts heretofore described are designated by similar but primed reference numerals. The socket is 125

similar in structure to that illustrated in Figs. 1 to 7 inclusive, the socket-tube being, however, extended rearwardly so as to be received through a central aperture 71 in the rear end of the outer casing of the lamp-body, this aperture being in the line of the principal axis of the reflector. The socket is further provided with rear terminals 72, 73, projecting outwardly from the sleeves 59', 60', and arranged to have contact made therewith by the terminals 74, 75, of an outer plug 76, with which outer flexible electric conductors 77, 78, electrically connect. The outer end of the socket-tube or member 15 is provided with bayonet slots 79 in which the pins 80 on the plug 76 are received for forming bayonet connection between the plug and outer end of the socket-tube or member.

20 The holding properties of the spring 51 and shoe 33 and the coacting surfaces of the socket-member will ordinarily also not be sufficient to counteract the manual force exerted in rotary and axial lines in connecting the outer plug 76 with the socket-member, in consequence of which the socket-member will be pushed axially inwardly and rotated by the outer plug. This axial movement is, in the present exemplification, a forward movement.

30 My improved construction provides a wide range of rotative and axial movements, or a wide range of movement which is the sum of these two movements of the electric 35 light-bulb, for its adjustment to desired focus, but limits the axial movement for permitting the attachment of the plug of the electric light-bulb to the socket-member from the inside of the reflector, or the attachment 40 of an outside connector-plug, such as the plug 26, to the outer end of the socket-member, when such structure is desired, and also prevents excessive rotary movement of the 45 socket for preventing twisting or tangling of the flexible electric conductor or conductors at the rear end of the socket.

The limit of axial movement of the socket-member is provided by contact of the end walls 39, 40, with the finger 41, the movement 50 of the finger axially being limited by the end walls 46, 47 of the opening 43 in the flange or lamp-member, as clearly seen in Figs. 1 and 7. The rotative movement of the socket is limited by contact of the finger 55 41 with the side walls 37, 38, of the recess 36 of the socket-member and with the side walls 44, 45, of the opening 43 in the flange, as clearly seen by comparison of Figs. 4, 5 and 6, the presence of the opening 43 in the 60 flange permitting a wide range of rotative adjustment while allowing the recess 36 to be made comparatively narrow, thereby avoiding the cutting away of much metal of the socket-tube or member.

65 My invention further provides ready

means for assembling the parts and provides parts which are easily and cheaply constructed, the socket-member, finger-piece and spring being constructed and assembled as separate parts. The socket-tube or member is arranged to be received in the lamp-member or flange with the recess 36 and opening 43 in coincidence. The plate 42 is then placed about the flange with its finger 41 received through the opening and into the recess, and the spring 51 then received about the flange and plate, with the shoe 33 extending through the opening 34 in the flange into contact with the retarding surface of the socket-tube or member, thereby readily assembling the parts in readily detachable relation.

Having thus fully described my invention, what I claim as new and desire to secure by Letters Patent, is:

1. In an electric lamp, the combination of a reflector, a lamp-member, a socket-member guided by the latter, means whereby said socket-member is arranged for movement manually about the line of the principal axis of said reflector, and a movement-limiting part arranged to be moved rotatively by said socket-member and said socket-member arranged to be moved rotatively relative to said movement-limiting part, said lamp-member arranged for limiting the rotative movement of said movement-limiting part during said rotative movement of said socket member relative to said movement-limiting part.

2. In an electric lamp, the combination of a reflector, a lamp-member, a socket-member guided by the latter for movement in any direction lengthwise of and rotatively about the line of the principal axis of said reflector, means remaining automatically effective for retaining said socket-member in adjusted positions, and a member coacting with said socket-member limiting said rotative movements of said socket-member arranged for being rotatively moved by said socket-member, and said socket-member arranged to be moved rotatively relative to said last-named member.

3. In an electric lamp, the combination of a reflector, a lamp-member, a socket-member provided with retardant surface-formations having movement in said lamp-member in any direction lengthwise of or rotatively about the line of the principal axis of said reflector, a position-retaining part provided with a coacting surface, a shiftable movement-limiting part for said socket-member, and resiliently acting means for said position-retaining part and for frictionally holding said movement-limiting part.

4. In an electric lamp, the combination of a reflector, a flange about the line of the principal axis of said reflector, a socket-member therein guided thereby and having

movement in said flange in any direction lengthwise of or rotatively about said line, said socket-member provided with an opening, said flange provided with an opening, a 5 finger received through said opening in said flange into said opening in said socket-member, said openings having end walls and side walls, the side walls of one of said openings being spaced apart substantially greater 10 than the thickness of said finger, and the respective end walls and side walls of the other of said openings being spaced apart substantially greater than the thickness of said finger, a position-retaining part coacting 15 with said socket-member, and a spring-band received about said flange acting on said last-named part and on said finger whereby said socket-member has movement in said lamp-member in any direction 20 lengthwise of or rotatively about the line of the principal axis of said reflector and said movements in each of said directions is limited.

5. In an electric lamp, the combination of 25 a reflector, a flange about the line of the principal axis of said reflector, a socket-member therein arranged whereby said socket-member has movement in said flange in any direction lengthwise of or rotatively about the line of the principal axis of said reflector, said socket-member provided with a recess, said flange provided with an opening, said recess and opening having end 30 walls and side walls, and a finger-plate provided with a finger received through said opening into said recess, the walls of said recess being movable with relation to said finger during a portion of the range of movement of said socket-member, and said finger being movable with relation to the walls of said opening during another portion of the range of movement of said socket-member.

6. In an electric lamp, the combination of 45 a reflector, a lamp-member in the form of a flange about the line of the principal axis of the reflector, a socket-member having movement in said flange in any direction lengthwise of or about said line of said principal 50 axis, said socket-member provided with a recess having side walls and end walls respectively spaced apart, said flange provided with an opening having side walls and end walls, a finger-plate about said flange having a finger received through said open-

ing into said recess, and a position-retaining part for said socket-member comprising a spring-band received about said flange and said finger-plate whereby said finger-plate is frictionally held about said flange. 60

7. In an electric lamp, the combination of a reflector, a lamp-member in the form of a flange about the line of the principal axis of the reflector, a socket-member having movement in said flange in any direction 65 lengthwise of or about said line, said socket-member provided with a recess having side walls and end walls respectively spaced apart, said flange provided with an opening having side walls and end walls, a finger-plate about said flange having a finger received through said opening into said recess, and a position-retaining part for said socket-member comprising a spring-band received about said flange and said finger-plate whereby said finger-plate is frictionally held about said flange, said socket-member having movement with relation to said finger throughout the range of the space between said finger and the walls of said recess and said finger-plate moved by said socket-member throughout the range of the space between said finger and the walls of 70 said opening. 75

8. In an electric lamp, the combination of 80 a casing and a reflector having a space therebetween, a flange in said space about the line of the principal axis of the reflector, a socket-member in said flange, said socket-member provided with a recess, said 85 flange provided with an opening, a finger-plate about said flange provided with a finger extending through said opening into said recess, a shoe received through said flange against said socket-member, and a spring-band pressing said shoe toward said 90 socket-member and said finger-plate toward said flange, and arranged for manual adjustment of said socket-member in any direction lengthwise of or about the line of the 95 principal axis of said reflector and for limiting the range of said movements. 100

In testimony whereof, I have hereunto signed my name in the presence of two subscribing witnesses.
